Herbert R. Carpenter, Chicago, Ill., assignor to
Dominion Electric Corporation

Filed June 25, 1962, Ser. No. 70,666

Term of patent 14 years

(Cl. D81—10)

FIG. 1

FIG. 2

FIGURE 1 is a view of a waffle grill of two parts having the uprightly disposed upper part carrying a grid showing my new design for four quarter-sections of the grid; and

FIGURE 2 is a view of the said waffle grill having the horizontally disposed lower part carrying a grid showing my new design for four quarter-sections of the grid corresponding to the grid shown in FIGURE 1.

The top and bottom surfaces of the grill not illustrated are substantially plain. The bottom surfaces of the grids not illustrated are substantially plain.

The dominant features of my design are shown in full lines.

I claim:

The ornamental design for a waffle grill, substantially as shown and described.
